UNITED STATES PATENT OFFICE.

ETIENNE WITZBERGER, OF CARNEGIE, PENNSYLVANIA, ASSIGNOR TO WITZBERGER HEATING APPLIANCES COMPANY, A CORPORATION OF PENNSYLVANIA.

MOVABLE REFLECTOR HEATER.

1,426,238.

Specification of Letters Patent. Patented Aug. 15, 1922.

Application filed November 15, 1921. Serial No. 515,395.

To all whom it may concern:

Be it known that I, ETIENNE WITZBERGER, a citizen of the United States, residing at Glendale, Carnegie, in the county of Allegheny and State of Pennsylvania, have invented new and useful Improvements in Movable Reflector Heaters, of which the following is a specification.

This invention relates to heating devices, and more particularly to what I term a movable reflector heater.

One of the main objects of the invention is to provide a heater having a movable reflector by means of which the heat is uniformly distributed through the room or apartment to be heated. A further object is to provide a heater including a fireback and means for causing air to circulate through the fireback so as to be heated thereby, this heated air being distributed by the reflector, the circulation of air through the fireback serving to prevent overheating thereof and also permitting the heat which is retained by the fireback, after the heater is extinguished, to be utilized to advantage. Further objects will appear from the detailed description.

In the drawings:

Figure 1 is a front view of the heater; Figure 2 is a central vertical section through the heater taken from front to back;

Figure 3 is a fragmentary sectional detail of the mounting of the reflector;

Figure 4 is a fragmentary detail back view of the reflector mounting;

Figure 5 is a detail of the means for reciprocating the reflector operating rod;

Figure 6 is a horizontal sectional view;

Figure 7 is a fragmentary sectional view taken substantially on line 7—7 of Figure 2, parts being omitted for clearness.

The heater includes a sheet metal casing 1 having back and end walls 2 and 3, respectively. At the forward edge of each end wall 1 I provide a supporting post 4 of sheet metal secured to end wall 3 by bolts 5, or in any other suitable or preferred manner. This post is provided at its upper end with a flared portion forming a cup 6 which receives the body portion of a flambeau like container 7 having a depending neck 7^b which fits snugly in the upper portion of post 4. The top or cover 7^a of the container is provided with perforations 8. This container is adapted to contain water so as to

provide a certain amount of moisture, the water being evaporated by the heat radiated from the heater, as will be understood. If desired perfumed water may be placed in the containers, but the principal object in providing the containers is to provide simple and efficient means whereby a moist heat is produced. Suitable foot members 9 are provided at the lower ends of posts 4 and co-operate with similar foot members 9^a secured to a bottom plate 10 which connects end plates 3 and back plate 2, to support the casing.

A front plate 11 connects posts 4. This front plate is secured by an angle strip 12 to the outer portion of a lower reflector plate 13 which fits snugly between end walls 3 and about posts 4. This reflector plate is shaped to provide two arcuate reflecting surfaces 13^a which are separated by a raised element 13^b. The inner portions of these reflecting surfaces 13^a act to reflect the heat laterally of the casing 1 thus obtaining a uniform distribution of the heat and also serving to heat the containers sufficiently to cause vaporizing of the water contained thereby for the purpose above set forth.

The inner edge portion of reflector plate 13 is supported upon a forwardly extending flange 14 provided at the lower edge of a supporting frame 15, this frame being provided with front and back end flanges 16 and 17, respectively, and a back lower flange 18. The frame is supported between end walls 3 by angle strips 19 secured to the end walls 3. This frame receives a fireback 20 of refractory material, this back being provided at each end with a forwardly projecting arm 21, the ends of the back fitting snugly between flanges 16 and 17 of frame 15, this frame being provided with webs 22 which hold the back against lateral movement. Webs 22 co-operate with end walls 23 of frame 15 to provide dead air spaces which serve to effectually prevent heating of end walls 3 from the fireback.

The upper portion of fireback 20 is turned downwardly and forwardly to provide, in effect, a hood 24 for reception of the products of combustion discharged from the upper ends of radiants 25 of refractory material which are positioned adjacent to the forward face of fireback 20 and between arms 21 of the fireback. These radiants are supported by hooks 26 carried by a dove-

tailed bar 27 which fits into a corresponding slot provided in the front face of fireback 20, this bar extending through end walls 3 and being secured in position by 5 caps 28 secured to the ends of the bar in any suitable or preferred manner. A perforated plate 29 of refractory material is mounted upon the upper face of bottom plate 30 of frame 15. Plate 29 is of channel 10 cross-section so as to leave a small space between this plate and plate 30, which latter plate is provided with a longitudinally extending slot for reception of the upper portion of a gas burner 31, the burner employed being preferably that illustrated in 15 my co-pending application 468,036; though any other suitable or preferred type of burner may be employed. The hooks 27 serve to relieve plate 29 of any pressure 20 which might be exerted by the radians 25, and by leaving a slight air space between plate 29 and plate 30 any possibility of warping of burner 31, due to the intense heat generated in the radians, is eliminated. 25 In addition, this air space acts, to a certain extent, as a mixing chamber to insure thorough mixing of the gas with a maximum amount of air so as to obtain complete combustion. Gas is supplied to 30 burner 31 by a valve 32 of any suitable or preferred type which may be connected to the gas line in any desired manner. The products of combustion which are discharged from the upper end of radians 25 35 into hood 24 flow into a flue 33 extending through back wall 2, this flue being connected to a chimney in any suitable manner, it being understood that fireback 20 is provided with a suitable opening 34 to accommodate the inner end of the flue. 40

Fireback 20 is further provided with a vertically extending passage or duct 35 which extends from the lower end of the fireback and for the full length thereof and 45 through arms 21. The upper portion 35^a of this duct is directed rearwardly of the fireback so as to discharge air flowing through the passage 35 from the lower end thereof against a sheet metal reflector 36 of con- 50 cavo-convex cross-section and substantially semi-circular outline. This reflector is rock- ably mounted, adjaceent to each end, on back wall 2 of the casing by means of a pintle 37 secured in sleeves 38 formed on 55 the reflector, this pintle passing through the body of a U-shaped bracket 39 secured by a screw 40 on the upper edge of the back plate. This bracket is provided with two angularly disposed arms 41 which are positioned at opposite sides of the reflector 36. 60 Each of the arms receives an adjusting screw 42 which bears against a leaf spring 43 secured by means of screw 40 and nut 40^a to the opposite faces of bracket 39. This 65 provides a rockable mounting for the re-

flector, the springs 43 providing means for cushioning movement of the reflector in either direction and screws 42 providing means for adjusting these springs so as to positively limit movement of the reflector. 70 A counter-weight 44 is connected by an angle rod 45 and plate 46 to the central portion of the back of the reflector, this weight serving to balance the reflector so as to permit the same to be readily rocked in 75 either direction. Plate 46 is provided with an angularly disposed arm 47 to which is secured the upper end of a coil spring 48, the lower end of this spring being secured to the upper end of an operating rod 49 80 slidable through angle brackets 50 secured to back plate 2. The lower end of this rod rests upon a cam 51 secured on shaft 52 of a spring motor 53 positioned within the cas- 85 ing adjacent to back wall 2 and bottom plate 10. A gear 54 is secured upon the other end of shaft 52 and meshes with a pinion 55 which is secured upon the shaft of a fan or blower 56 secured to bottom plate 10. Outlet conduit 57 of the fan casing com- 90 municates with the lower end of a V-shaped manifold 58 the upper end of which fits into the lower portion of passage or conduit 35 of fireback 20. A winding rod 59 is rotatably mounted through end walls 3 and car- 95 ries a bevel gear 60 secured on the rod, this gear meshing with a bevel gear 61 secured on the inner end of shaft 52. A gravity pawl 62 is mounted on the casing of spring motor 53 and engages a ratchet-wheel 63 100 secured on shaft 52 adjacent to gear 54, the pawl and ratchet co-operating to prevent reverse rotation of the motor during wind- 105 ing thereof. In practice I use a motor which is capable of rotating the fan or 105 blower 56 for a period of approximately two hours and at such a speed as to cause a comparatively large volume of air to flow through duct or passage 35 of the fireback so as to be heated thereby to a comparatively 110 high temperature, when the heater has been in operation a sufficient length of time to heat the fireback, this heated air being dis- charged against the inner face of reflector 36 which is rocked slowly by cam 51 and 115 rod 49 so as to direct the stream of heated air alternately downwardly and upwardly thus obtaining a uniform distribution which greatly facilitates heating of the room or apartment in which the heater is positioned. 120 The spring 48 permits adjustment of the amplitude of rocking movement of the re- flector without in any way interfering with its operation by rod 49. To permit the flow of gas to be regulated I provide an opening 125 in front plate 11, this opening being normally closed by a door or closure plate 64 releasably secured in position by a spring catch 65.

When the heater is in operation, the gas 130

flows from burner 31 into the space between plates 31 and 29, and through the perforations of plate 29 into radiants 25 where it is ignited. The radiants become incandescent 5 so as to generate a great amount of heat which is reflected forwardly of the heater, a certain amount of this heat being reflected laterally by means of the arcuate reflecting surfaces 13^a of the plate 13 for the purpose 10 of heating the containers 7 and also for distributing the heat laterally of the heater. In addition, the products of combustion flowing into hood 24 serve to raise the down-turned front portion of the hood to a comparatively 15 high temperature which also produces a very decided heating effect supplementing the heating effect of the radiants. The air flowing through passage or duct 35 is heated to a high temperature and is distributed, by means of reflector 36, in the manner previously described. By constructing the heater in the manner illustrated and described I obtain a maximum amount of heat for a given quantity of fuel consumed 20 and also insure that this heat is distributed to the best advantage laterally and forwardly of the heater, a portion of the heat generated being utilized to vaporize the water in the containers so as to obtain a moist heat 25 which is very desirable.

I realize that it may be found desirable by experience to resort to changes in construction and arrangement of parts of the invention, and I intend to include all such variations, as fall within the scope of the appended claims, in this application in which the preferred form only of my invention is disclosed.

What I claim is:—

40 1. In a stove of the character described, a casing, a fireback supported in the casing and provided with a passage extending through the body of the back from the lower end thereof, heat generating means adjacent to the fireback, a rockably mounted deflector above and in rear of the fireback, the upper end of said passage being disposed to discharge air flowing through the passage against the deflector, and means for causing 45 air to flow through said passage from the lower end thereof and for imparting rocking movement to the deflector.

2. In a stove of the character described, a casing, a fireback supported in said casing, heat generating means adjacent to said fireback, the body of the fireback being provided with a passage extending from the lower end thereof, a rockably mounted deflector above and in rear of the fireback, 55 a blower having its outlet communicating

with the lower end of said passage, the upper end of the passage being disposed to direct air discharged therefrom against the deflector, an operating rod connected to the deflector for imparting movement thereto 65 when the rod is reciprocated, and means for operating said blower and the operating rod.

3. In a stove of the character described, a casing, a supporting frame mounted in the casing, a fireback mounted in said frame, a rod extending through the fireback and the ends of the casing, hooks carried by said rod and projecting beyond the front face of the fireback, radiants supported by said hooks, and means for heating said radiants. 70 75

4. In a stove of the character described, a casing provided at the forward edge of each end with a supporting post, containers for water or other liquids mounted in the upper ends of said posts, a fireback supported in 80 the casing, radiants mounted adjacent to the front face of the fireback, a burner positioned beneath said radiants for heating the same, and a reflector plate mounted in advance of the radiants, said plate being shaped 85 to provide two concaved reflecting surfaces for reflecting the heat from the radiants toward said containers so as to cause evaporation of liquid therein.

5. In a stove of the character described, 90 a casing, a fireback mounted in the casing and provided with an air passage extending through the back from the lower end thereof, radiants mounted adjacent to the front of the fireback, a burner positioned beneath 95 said radiants for heating the same, a reflector rockably mounted upon the casing above and in rear of the fireback, the upper end of said passage being disposed to direct air discharged therefrom against the reflector, means for causing air to flow through 100 said air passage from the lower end thereof and for imparting rocking movement to the reflector, and adjustable means for limiting movement of the reflector in either direction, 105 said means also acting to cushion movement of the reflector.

6. In a stove of the character described, a casing, a fireback mounted in the casing, radiants mounted adjacent to the front of 110 the fireback, a burner positioned beneath said radiants for heating the same, and a reflector plate mounted in advance of the radiants and shaped to provide two concaved reflecting surfaces disposed to reflect 115 the heat from said radiants laterally of the casing.

In testimony whereof I affix my signature.

ETIENNE WITZBERGER.
